UNITED STATES PATENT OFFICE.

EDWARD D. HILLMAN, OF LARCHMONT, NEW YORK, ASSIGNOR TO BENJAMIN A. HEGEMAN, JR., OF NORTH PLAINFIELD, NEW JERSEY.

HOPPER-CAR.

1,308,421.

Specification of Letters Patent.

Patented July 1, 1919.

Application filed March 6, 1917. Serial No. 152,625.

To all whom it may concern:

Be it known that I, EDWARD D. HILLMAN, a citizen of the United States, and a resident of Larchmont, in the county of Westchester and State of New York, have invented certain new and useful Improvements in Hopper-Cars, of which the following is a specification.

The invention pertains more particularly to hopper cars for carrying coal and other materials, and one of the purposes of the invention is to so dispose the hoppers and discharge doors as to very materially increase the cubical capacity of the car and lower its point of center of gravity. A further purpose of the invention is, while accomplishing the object hereinbefore mentioned, to increase the discharge area of the car, whereby the load may be more quickly discharged. A further object of the invention is to construct the car with a plurality of hoppers having discharge floors inclined in the same direction and so connect the doors of all the hoppers that said doors may be simultaneously opened and closed from an operating shaft extending transversely across the car, near the end thereof, and exposed at both ends so that the doors may be operated either to open or close from either side of the car. I also equip the car with an auxiliary operating shaft capable of actuation from either side of the car and having between the center sills of the car a projection, cam, arm or the like below the crank and link connection of the door operating mechanisms with the aforesaid operating shaft, so that by the partial rotation of said auxiliary shaft the door operating mechanisms may be initiated in motion and then left to complete their movement automatically and independently of said auxiliary shaft under the pressure of the coal or other substance against the discharge doors or gates, thus guarding the operator against any accidents which might otherwise happen were the auxiliary shaft to continue in motion during the opening of the doors or which would likely happen if the operator had to apply his wrench to the operating shaft and did not succeed in releasing it therefrom before the doors got fairly started in motion. I also provide efficient means for locking the operating shaft against motion when the doors are in closed position, and this mechanism, located at each

side of the car, is substantially identical with like mechanism shown and described in my pending application for Letters Patent bearing Serial No. 65,462 and filed December 7, 1915.

The invention will be fully understood from the detailed description hereinafter presented, reference being had to the accompanying drawings, in which:

Figure 1 is a central vertical longitudinal section through a portion of a hopper car embodying my invention, the section being taken between the center sills of the car, and Fig. 1 illustrates the several discharge doors for the hoppers in closed position;

Fig. 2 is a corresponding view of the same showing the several doors for the hoppers in their open position to permit the discharge of the load;

Fig. 3 is a vertical transverse section through the lower portion of the car taken on the dotted line 3-3 of Fig. 1;

Fig. 4 is a top view, partly sectioned and partly broken away, of a portion of a car, equipped with the features of my invention, the center sills being shown in top view, the hood over the same in section and a portion of the sides of the car being shown in section;

Fig. 5 is an enlarged top view, partly broken away, of the operating shaft and auxiliary or cam shaft controlling the operation of the doors;

Fig. 6 is a sectional view through adjoining portions of one pair of the doors and illustrates, among other details, the means for connecting the adjoining portions of the operating links utilized for imparting simultaneous opening and closing movements to the several doors, and

Fig. 7 is a detached side view of a portion of one side of the car and illustrates a portion of the control mechanism for the operating shaft, the mechanism shown in Fig. 7 being that illustrated in more complete detail in my aforesaid application for Letters Patent.

In the drawings, 10 designates portions of the hoppers which extend downwardly below the center sills 11 and are formed with side sheets 12 and inclined bottom sheets 13 down which, when permitted to do so, the coal or the like automatically discharges. The hoppers 10 are transverse of the car and in the construction presented I illustrate

four of said hoppers, at each side of the center sills, although not intending to limit my invention to the employment of any specific number of the hoppers. The bottoms 13 of 5 the hoppers all incline in the same direction, and at the discharge portions of these hoppers are provided doors or gates 14 which are hinged at their upper ends, as at 15, to the bottom portions of adjacent hoppers and 10 near the center sills, the door for one hopper being secured at its upper end to the bottom portion of the next inwardly adjacent hopper. The doors or gates 14 all correspond with one another and the doors are connected 15 in transverse pairs, as shown more clearly in Fig. 3, by bulb beams 16 which are securely riveted to said gates or doors 14. The bulb beams 16 I deem of particular advantage in that they afford a broad flange 20 for application to the face of the door and at the same time the bulb portion of the beam, while affording requisite strength, occupies the minimum space, it being one of the purposes of my invention to economize space between the lower ends of the doors or gates 25 14 and the track on which the car may stand or be moving.

The doors or gates 14 are connected together in series by pivoted links 17, so that 30 all of the doors or gates may be operated simultaneously on both their opening and closing movements, as will be understood on reference to Figs. 1 and 2. The links 17 extend lengthwise of the car below the space 35 formed between the center sills 11, as may be understood by reference to Figs. 3 and 4, and the link 17 connected with the first outer or right hand door or gate 14, looking at Figs. 1 and 2, is pivotally connected with a 40 link 18 whose outer end is pivotally hung upon the transverse portion of a U-shaped bend or crank 19 formed at the center of the transverse operating shaft 20. The shaft 20 is preferably formed from a round rod and is 45 squared at its ends, as at 21, so that a wrench or other suitable tool may be applied to the shaft, more particularly in this case, for effecting the closing of the doors or gates 14. The links 17 have enlarged angular outer 50 end portions 22, and these portions are bifurcated or forked so that each may receive the forward end of the next adjacent link, the links being pivotally connected together by means of pins 23 extending transversely 55 through the forked portion of each link and the adjoining end of the link inserted within said portion. The forked portions 22 of the links 17 are also pivotally connected with the respective doors by means of transverse pins 60 24 which extend through said portions and through eye-bolts 25 (Fig. 6) which are secured to the central portions of the upper flanges of the bulb beams 16, an additional plate 26 being riveted against the web of the bulb beams for affording greater strength at 65

the points of connection of the eye-bolts 25 with said beams. The eye-bolts 25 are centrally of the beams 16 and between the inner side sheets of the hoppers. The forward link 17 terminating at the door or gate 14 at 70 the left, looking at Fig. 1, is bifurcated and pivotally connected by a transverse pin 27 with an eye-bolt 28 secured to said door and corresponding in all respects with the eye-bolt 25 shown on an enlarged scale in Fig. 6. 75 The outer link 18 enters at its inner end the fork 22 of the outer link 17, this being the link at the right, looking at Fig. 1, and is pivotally connected with said link 17 by means of a transverse pin 29. The outer end 80 of the link 18 is apertured to slip upon the shaft 20 and reach the position in the bend or crank 19 thereof, as illustrated in Fig. 5.

The shaft 20 is a crank shaft, the crank being formed by the bend 19, and when said shaft is turned to move the doors 14 to their closed position, the crank 19 carries the link 18 outwardly to the position shown in Figs. 1 and 4, in which the outer pivoted end of the link is below a center line drawn through the pin 29 and said shaft 20, whereby the doors 14 become locked in their closed position. The ends of the shaft 20 extend beyond the sides of the car and are squared, at 21, as hereinbefore explained, so that an 95 operator by means of a wrench may rotate said shaft from either side of the car for the purpose of closing the doors 14 or opening the same if necessary.

In addition to locking the doors 14 in 100 their closed position by providing a mechanism passing beyond the aforesaid dead center, I also provide at each side of the car the additional mechanism illustrated more fully in Fig. 7 and made the subject of my 105 aforesaid application for Letters Patent filed December 7, 1915, and this mechanism may be called an auxiliary locking mechanism or pawl and ratchet mechanism, and comprises a toothed disk 30 on each end of the shaft 20, pivoted dogs or pawl arms 31 adjacent to said disks and each having a tooth 32 adapted to engage a tooth on the disk 30, and crank arms 33 having loose connection, by a pin and slot, with the pivoted arms 31, all this being shown in my aforesaid application. The crank arms 33 are secured on the ends of an auxiliary shaft 34 which extends beyond the sides of the car and has squared ends adapted to 110 receive a wrench or other suitable tool. On the central portion of the auxiliary shaft 34 is secured a cam or crank arm or the like 35, and this member 35 is below the location of the crank 19 of the operating shaft 20 115 and the outer end of the link 18 when the doors 14 are in closed position and held closed either by the outer end of the link 18 passing beyond the center line, hereinbefore mentioned, or by the auxiliary locking 120

130

means shown in Fig. 7 or by both such means. It has frequently been customary for an operator attempting to open the doors of a hopper car to apply his wrench on an 5 operating shaft, such as that numbered 20 herein, and upon the opening of the doors the sudden impulse given to them by the pressure of the load has frequently resulted in the operating shaft turning so rapidly 10 that the operator could not remove his wrench therefrom, the wrench being violently thrown from the shaft and the operator placed in danger. According to my 15 present invention the auxiliary shaft 34 is utilized for initiating the doors 14 on their opening movement, and this result is effected by the operator applying his wrench or similar tool to the end of the shaft 34 and turning said shaft to cause the crank 20 arm or cam 35 thereon to move upwardly against the crank 19 or outer end of the link 18, or both, to a sufficient extent to move the outer end of said link 18 upwardly above the dead center line, hereinbefore 25 mentioned, whereupon without any further strain on or rotation of the shaft 34 or any danger to the operator, the load pressing against the doors 14 will instantly drive them to their open or discharge position. 30 It will thus be seen that with the use of the auxiliary shaft 34 and crank arm or cam 35 thereon, the doors 14 may be initiated in movement and will then open automatically, without danger to the operator. It 35 is to be observed also that the means I provide for initiating the opening movement of the doors 14 is one of great durability and extreme simplicity.

I mount the crank arms 33 on the ends 40 of the shaft 34 so that upon the turning of said shaft to initiate the opening movement of the doors 14, said arms 33 may turn the pawl or dog arms 31 from engagement with the toothed disks or wheels 30, thus freeing 45 the operating shaft 20 for rotation, and that on the continued movement of the shaft 34, the cam or crank arm 35 is caused to act against the crank of the operating shaft 20 to effect the opening of the doors 14. Upon 50 the opening of the doors 14, the cam 35 becomes by the rotation of the shaft 34 displaced from its lower position, and the dog arms 31 become set outwardly from the disks 30. When by means of the shaft 20 the 55 doors 14 are moved to their closed position, the crank 19 or link 18 strikes the cam 35 and turns it downwardly to its normal position, thereby rotating the shaft 34 to a limited extent, all this having the effect of permitting the link 18 and outer end of crank 19 to go by the center line, for locking the doors in closed position, and also causing the dog arms 31 to reengage the disks 30 for further locking the doors 14 in closed 60 position.

My invention involves the construction of a car with downwardly and inwardly inclined end bottom sheets 36 of usual type and a series of hoppers 10 intermediate the lower ends of said bottom sheets 36 and substantially below the floor line of the car, 70 the upper ends of said hoppers being about in line with the horizontal plane of the lower edges of the car sills and extending downwardly as nearly as convenient to the line of road bed. The inclined bottoms of the hoppers 10 preferably incline in the same direction, and as hereinbefore described the doors 14 for these hoppers are connected together in series by links and 75 thence with the operating shaft 20 so that said doors may all have simultaneous opening and closing movements. It will be observed, without special comment, that the presence of the hoppers 10 arranged as 80 described increases the cubical capacity of the car, since they are below the floor line of the car and do not occupy space which hoppers have heretofore occupied within the body of the car. It will also be seen that the 85 presence of the hoppers 10 brings the center of gravity of the load closer to the road bed, and that the plurality of hoppers 10, with their discharge doors 14, increase the discharge area of the car, thus permitting the 90 car to more rapidly become discharged of its contents.

The shafts 20, 34 are suitably mounted in brackets which may be of varied construction and therefore not necessary to be described, one suitable form being illustrated 95 in Figs. 1 and 2.

The center sills 11 will be covered over by a hood 37, as usual.

What I claim as my invention and desire 100 to secure by Letters-Patent, is:

1. A hopper car having a plurality of hoppers extending downwardly below the sills thereof with the floors of the hoppers below said sills inclined in the same direction, hinged downwardly extending doors for the discharge ends of said hoppers, links connecting said doors in series for securing simultaneous movement thereof, a transverse operating shaft for said doors having 105 a crank portion, and a pivoted link connecting the crank portion of said shaft with said series of doors and links, said crank portion being adapted to carry the outer end of said link on the closing of the doors below a center line through the shaft and the inner end of the link for thereby locking the doors in closed position, combined with means independent of said shaft for turning the same to cause said crank portion to 110 carry the outer end of said link above said center line, thereby leaving the said doors to open automatically.
2. A hopper car having downwardly and 115 inwardly inclined end plates and intermedi-

ate said plates a plurality of hoppers extending downwardly from about the horizontal plane of the car sills with the floors thereof inclined in the same direction, 5 hinged downwardly extending doors for the discharge ends of said hoppers, links connecting said doors in series for securing simultaneous movement thereof, a transverse operating shaft for said doors having a 10 crank portion, and a pivoted link connecting the crank portion of said shaft with said series of doors and links, said crank portion being adapted to carry the outer end of said link on the closing of the doors below 15 a center line through the shaft and the inner end of the link for thereby locking the doors in closed position, combined with means independent of said shaft for turning the same to cause said crank portion to carry the 20 outer end of said link above said center line, thereby leaving the said doors to open automatically.

3. A hopper car having downwardly and inwardly inclined end plates, and intermediate 25 said plates and at and below the floor line of the car a plurality of hoppers with the floors thereof inclined in the same direction, hinged downwardly extending doors for the discharge ends of said hoppers, an 30 operating shaft and means intermediate said shaft and said doors for simultaneously operating the same, said shaft being connected with the means connecting the doors by a link adapted when the doors are approaching their closed position to at its 35 outer end pass below a center line extending through the inner end of the link and said shaft, thereby locking the doors in closed position, combined with means independent 40 of said operating shaft for initiating said shaft in motion so that when the outer end of said link is moved upwardly beyond said center line, the said doors may open automatically.

45 4. A hopper car having longitudinal center sills and downwardly and inwardly inclined end plates and intermediate said plates hinged downwardly extending doors

for the discharge of the load, an operating shaft connected with said doors and having 50 a crank portion at the space below said center sills, an auxiliary operating shaft having crank means thereon below the crank portion of said operating shaft for initiating the same in motion, means associated with 55 said operating shaft for locking the same against motion when the doors are in closed position, and means associated with said auxiliary shaft for releasing the operating shaft preparatory to said shaft being thus 60 initiated in motion.

5. A hopper car having downwardly and inwardly inclined end plates, and intermediate 65 said plates hinged downwardly extending doors for the discharge of the load, an operating shaft having a crank portion connected with said doors for operating the same, an auxiliary shaft having means thereon below the crank portion of said operating shaft for initiating the same in 70 motion, pawl and ratchet mechanism associated with said operating shaft for locking the same against motion when the doors are in closed position, and means associated with 75 said auxiliary shaft for releasing the operating shaft preparatory to said shaft being thus initiated in motion.

6. A hopper car having downwardly and inwardly inclined end plates, center sills, 80 hoppers at each side of said center sills, an operating crank shaft connected with said doors for operating the same, and an auxiliary shaft having a crank portion thereon for initiating the operating shaft in motion, 85 said operating and auxiliary shafts extending transversely of the car and being exposed at both ends so that the shafts may be operated from either side of the car.

Signed at New York city, in the county of New York and State of New York, this 90 5th day of March, 1917.

EDWARD D. HILLMAN.
